US0D1106081S

(12) **United States Design Patent** (10) **Patent No.:** **US D1,106,081 S**
(45) **Date of Patent:** **** Dec. 16, 2025**

(54) **CONNECTOR HOUSING**

(71) Applicant: **Japan Aviation Electronics Industry, Limited**, Tokyo (JP)

(72) Inventors: **Yukuya Morishita**, Tokyo (JP); **Yusuke Obata**, Tokyo (JP)

(73) Assignee: **Japan Aviation Electronics Industry, Limited**, Tokyo (JP)

(**) Term: **15 Years**

(21) Appl. No.: **29/906,734**

(22) Filed: **Nov. 9, 2023**

(30) **Foreign Application Priority Data**

May 26, 2023 (JP) ..... 2023-010658 D

(51) **LOC (15) Cl.** **13-03**

(52) **U.S. Cl.**

USPC **D13/147**

(58) **Field of Classification Search**

USPC D13/147, 146, 199, 184, 120, 133, 173, D13/154, 108

(57) **CLAIM**

The ornamental design for a connector housing as shown and described.

DESCRIPTION

FIG. 1 is a front elevational view of a connector housing showing our new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a front, top, and right side perspective view thereof;

FIG. 8 is a rear, bottom, and left side perspective view thereof;

FIG. 9 is a front, right, and bottom side perspective view thereof; and,

FIG. 10 is a rear, left, and top side perspective view thereof. The broken line showing of the connector housing is for the purpose of illustrating portions of the article and forms no part of the claimed design.

1 Claim, 8 Drawing Sheets
